4 Claims. (Cl. 25—82)

This invention relates to an apparatus for pressing plastic masses and particularly ceramic masses between relatively movable press dies.

Generally speaking, plastic masses, and particularly ceramic masses, are pressed by pressing a suitably prepared cake into its final form between press dies, both of which are movable or one of which is movable and the other fixed.

This operation is carried out mechanically, hydraulically, pneumatically, magnetically or in like fashion, if desired with the superimposition of vibrations or with the use of heat, electric charges or electric currents. In the methods of pressing plastic, and particularly ceramic masses known heretofore the press dies are arranged to be parallel to one another and to maintain this parallelism during the pressing operation. In numerous cases considerable effort is made carefully to maintain this parallelism of the press dies during the pressing operation. However, in a pressing operation of this character there arises the difficulty of eliminating the air imprisoned in the prepared press cake, particularly the air bubbles or air-filled spaces formed during the pressing operation. Without the elimination of these hollow spaces or air bubbles the production of a pressed article of a satisfactory nature is practically impossible.

It has accordingly been attempted to remove in various ways the air from the mass during the pressing operation. One known proposal consists in first moving the press dies towards each other and then once or several times first away from and then towards one another, in order in this manner to permit escape of air upon each pressing movement. In the invention a completely new procedure is adopted and a departure is made from the hitherto customary practice of arranging the press dies parallel to one another and of maintaining this parallelism of the dies during the pressing operation.

The apparatus according to the invention functions to carry out the pressing operation with such a relative movement between the upper and lower press dies that the relative speed of one end of the dies differs from that of the other end of the dies. For example, the pressing operation may take place by a surface rolling action of the top die over the lower die which receives the material to be pressed. It is also possible in accordance with the invention to superimpose in known manner a vibratory movement on the novel relative movement of the press dies. It is also possible to perform the pressing operation under the influence of heat which may be effected by induction currents.

Typically the apparatus of the invention consists, for example, in the provision of the press dies in the form

2

of a pair of tongs, so that they can be moved towards one another along an arc.

The fundamental idea according to the invention may be applied with particular advantage to rotary presses for the production of ceramic articles or the like.

It has already been proposed in the case of rotary presses for roofing tiles to mechanize to a large extent or even to render completely automatic the work of these presses. However, in carrying this into effect it has been necessary in the known presses to accept as inevitable an increase in the diameter of the turret and accordingly an increase in the number of moulds on the turret, i.e. to increase the number of moulds from five to from nine to eleven. A further improvement in the mechanization or conversion to automatically of these rotary presses was envisaged by the change over from a horizontal turret to a rotary table having horizontal or tiltable moulds or to rotary table presses of truncated form. However, in the latter case it is necessary to dispense with the main advantage of a turret, viz., the fact that the article being pressed moves automatically upon rotation of the turret into a position for delivery for further treatment and particularly for removal of the finished article without the moulds collapsing and without the necessity for auxiliary tools.

A further disadvantage resulting from an increase in the diameter of the turret for the purpose of obtaining automatic operation consists in the fact that, owing to the construction of the supporting structure, access to the sides of the turret and accordingly to the individual moulds, is rendered extremely difficult. If in such a construction automatic delivery of the clay cake, automatic removal of the burr, automatic smoothing, automatic removal of the finished article, and so forth, were contemplated, access to the moulds and accordingly the possibility of cleaning them and maintaining them under observation would be completely prevented.

These disadvantages may be avoided by use of the principles of the invention as applied to rotary presses, there being possible not only a complete mechanization of the pressing operation but also adequate elimination of the hollow spaces or air bubbles in the article being pressed.

In the rotary press according to the invention the turret is mounted in cantilever fashion, making use of the principle of different relative speeds of the two ends of the top and bottom dies, so that despite the lever mechanism, etc., necessary to mechanize the pressing operation the turret is well accessible from the side. All operation on the rotary press according to the invention can be readily observed and controlled. Replacement of the dies may be performed from the side much simpler and quicker than in the case of rotary presses with turrets supported on both sides as known heretofore.

In the press according to the invention the principle of different relative speeds of the two ends of the top and bottom dies is preferably effected by constructing the ram of the press as a pivoted element having a toggle-lever drive adapted to the pressure characteristic of clay materials. The toggle-lever drive consists of a pressure and tension lever system by which it is possible to locate the entire drive towards the rear behind the bearing for the spindle of the turret, so that additional space for the turret is obtained, and the drive is not effected from above as heretofore.

A pivoted element for the ram of the press, which is mounted and driven in the manner described, also has the

advantage that the extent of movement of the press die can be adjusted simply. For example, the toggle-lever mechanism may be driven by means of a crank drive, although any other mechanical drive or a pneumatic, hydraulic or other drive is also possible. When employing a crank drive it is possible, for example, by varying the length of the connecting rod, to exceed the dead centre position and accordingly to achieve a double stroke, i.e. a two fold pressing operation, with one revolution of the crank. It is a pressing operation of this nature which is admirably suited for many ceramic substances, as it is possible to expel the air from the material being pressed. If it be desired to effect a further pressing out of the material after relief of the pressure, the pressure bearing of the toggle lever is so adjusted—coupling being effected with the toggle-lever drive during the intermediate lifting movement—that the rearward movement of the toggle lever draws the die further downwards than upon the forward movement. On the further return movement the opposite bearing, which is preferably constructed as an eccentric, again assumes the position necessary for initiation of the first movement.

Should a further adjustability of the stroke be desired, for example for adaptation to the consistency of the material being processed and to progressive wear on the dies of the press, this may advantageously be effected in accordance with the invention by adjustment of the tension bearing for the toggle lever in the pivoted element. In contradistinction to known constructions this adjustment may be effected extremely simply, for example by the adjustment of an eccentric, without it being necessary to remove any parts from the machine or to use attachments or the like.

An additional advantage of the construction according to the invention is that the pivoted element forming the ram of the press enables a turning of the turret to be avoided and complete relief of the turret drive, for example a Geneva mechanism, to be obtained during the action of the powerful forces occurring during the pressing operation.

In the accompanying drawings:

Figure 1 is a diagrammatical view illustrating the principle of the invention;

Figure 2 is an elevational view of a rotary press constructed according to the invention, and

Figure 3 is an end view of the press as seen from the left of Figure 2.

According to Figure 1 the two press dies 1, 2 are mounted on arms 3, 4 respectively of a tongs-like member, for example by means of screws 5, 6. The arms 3 and 4 are pivotally mounted on a shaft 7 and may be moved towards one another.

In the pressing operation the inner end 8 of the upper press die 2 first enters into contact with the material located on the lower press die 1, so that the pressing operation commences at this point and then progresses to the other end 9 of the upper die until finally the desired end position is reached, in which the two dies are located practically parallel to one another. In this manner the mass being pressed undergoes a general flowing movement in the direction from the first towards the subsequently contacting end. This general direction of flow may naturally have superimposed thereon local currents dependent on the particular form of the article being pressed. It has been found that when carrying out operations with a press thus constructed the air imprisoned in the material is expelled practically in its entirety.

If desired, the pressing operation according to the invention may also be carried out with a preliminary or subsequent pressing of the material or with repeated pressing. The embodiment illustrated is merely intended to show the principle of the invention.

For the sake of simplicity the drawings illustrate as an example a pressing operation making use of prepared press cakes. The improved method may also be em-

ployed in similar fashion using lumpy or granular substances; also a dry pressing operation may be utilised in place of the pressing of plastic substances as described.

In the rotary press illustrated in Figures 2 and 3 the turret 11 is mounted on bearings 13 which are indicated diagrammatically and which in turn are mounted on a journal 12. This journal 12 is supported in the casing 14 of the rotary press at the points 16 and 17 constituting cantilever-like supporting or bearing surfaces. The drive of the turret 11 is effected by means of the shaft 18 through the medium of the Geneva mechanism 19 and the driving wheel 20.

On a pivoted member 21 is mounted the upper die 22 and the lower dies 23 are provided on the turret. As can be seen from Figure 2, the upper die 22 may be readily removed towards the left, no obstruction being encountered by reason of bearing structures or the like.

The member 21 pivots about the pivot 24 and is driven by a toggle-lever system 25 which comprises the toggle levers 26, 27. The toggle lever 26 is a tension lever and the lever 27 is a pressure lever. The bearing 28 in the casing 14 may be adjusted eccentrically. The tension bearing 29 in the pivoted member 21 is also eccentrically adjustable, so that adjustment of the toggle-lever mechanism is possible both by way of the eccentric mounting of the bearing 28 as well as the eccentric mounting of the tension bearing 29. The connecting rod 30 is secured to the crank 31 and is adjustable in its length, so that if necessary the toggle-lever system 25 may be moved beyond its dead centre position indicated at 32, the pivoted member 21 and with it the upper die 22 being somewhat lifted.

For the purpose of relieving the Geneva mechanism 19 for the turret there is provided in accordance with an additional feature of the invention a device which enters into operation upon the lowering of the pivoted member 21 and takes up the considerable lateral forces which may occur during the pressing out by the die. The pivoted member is furnished with a guide bolt 33 engaging in slideways 34 on the frame 14 of the machine. Upon further downward movement the projection 35 on the guide bolt engages in slideways in the turret. In this way there is established during the pressing out operation a rigid connection between the turret 11, the casing 14 and the pivoted member 21 against forces occurring vertically to the plane of Figure 2.

We claim:

1. A rotary press for plastic masses comprising a frame, a turret having a plurality of dies, a cantilever-like support in one end of the frame for one end of said turret, an arm pivotally mounted on said frame with the pivot remote from said turret carrying frame end, a die carried by said arm for recurrent cooperation with said turret dies respectively, means comprising a toggle lever mechanism including lever means pivotally interconnected between said frame and said arm for imparting rocking movement to said arm, whereby pressure is applied to a plastic mass first at one end of the respective dies and then progressing along the mass to the other ends of the dies, means to impart step-by-step turning movement to said turret, guide means on said frame adjacent said turret, and means on said arm cooperating with said guide means for militating against lateral displacement between said turret and pivoted arm during the pressing operation.

2. A rotary press as claimed in claim 1 in which said last mentioned means comprises a guide bolt depending from said pivoted arm, and said guide means comprises a rigid guide on said frame into which said bolt slides.

3. A rotary press as claimed in claim 2 comprising a projection on said guide bolt, and slideways on said turret into which said projection extends thereby to establish a rigid connection between said turret, frame, and pivoted arm against vertical forces.

4. A rotary press as claimed in claim 1 including bearing means for said toggle lever mechanism, and eccentric

means for adjusting at least one of said bearings thereby to regulate the stroke of said toggle mechanism.
